(57) **CLAIM**

We claim the ornamental micro-dosing device, as shown and described.

DESCRIPTION

FIG. 1 is a front, right, and above perspective view of a micro-dosing device;

FIG. 2 is a back, left, and below perspective view thereof;

FIG. 3 is a back elevation view thereof;

FIG. 4 is a front elevation view thereof;

FIG. 5 is a left side elevation view thereof;

FIG. 6 is a right side elevation thereof;

FIG. 7 a top plan view thereof; and,

FIG. 8 is a bottom plan view thereof.

The broken lines in the drawings illustrate portions of the micro-dosing device and form no part of the claimed design.
